UNITED STATES PATENT OFFICE.

OTTO ROESLER, OF PHILADELPHIA, PENNSYLVANIA.

DANGER-SIGNAL ATTACHMENT FOR LOCOMOTIVES.

Application filed September 17, 1926. Serial No. 136,082.

This invention relates generally to attachments for locomotives, and has more particular reference to a novel type of attachment for automatically operating the locomotive whistle when a danger signal is passed.

The invention has for an object the provision of an improved device of the above mentioned character which will be positive in operation, capable of being readily installed, and which can be manufactured and sold at a low cost.

For further comprehension of the invention, and of the objects and advantages thereof, reference will be had to the following description and accompanying drawings, and to the appended claims in which the various novel features of the invention are more particularly set forth.

Referring to the drawings forming a material part of this disclosure:

Fig. 1 is a side elevational view of a locomotive with the invention device applied thereto.

Fig. 2 is a vertical sectional view taken on the line 2—2 of Fig. 1.

Fig. 3 is a fragmentary vertical sectional view taken on the line 3—3 of Fig. 2.

Fig. 4 is a view similar to Fig. 3, but of a slightly modified form of cam element, and the trip lever mechanism not being shown.

Fig. 5 is a fragmentary enlarged partly sectional side view of the mechanism intimately associated with the whistle.

Fig. 6 is a vertical sectional view taken on the line 6—6 of Fig. 5.

Fig. 7 is a fragmentary enlarged side elevational view of the trip lever mechanism.

Fig. 8 is a plan view thereof.

Fig. 9 is a side elevational view thereof.

Fig. 10 is a front view of a signal with certain mechanism applied thereto for operating the cam element.

Fig. 11 is a plan view thereof.

Fig. 12 is a plan view of the cam element.

Fig. 13 is a side view thereof.

Fig. 14 is a fragmentary side view of a flexible connection between the signal and the cam element.

Fig. 15 is a plan schematic view of the invention device applied to a switch, to give warning when the switch is opened or closed.

The reference numeral 15 indicates a loco-

motive having a customary steam whistle 16. The locomotive rests on rails 17, and adjacent said rails, a signal 18 supported on post 19 is shown. The top of rod 20 is pivotally connected with the signal 18, and the bottom engages the arm 21 of a pivotally mounted gear segment 22, meshing with rack 23, slidably guided by support 24 and connected to one end of rod 25, to the other end of which cam element 26 is fastened. 60 The cam element 26 is slideable in grooves 27 of bracket 28 which is fastened to the ties 29, supporting rails 17.

Beneath the locomotive 15, a bracket 29 is fastened. The bracket 29 has a pair of upwardly projecting tongues 30 adjacent an aperture 31, another upwardly projecting tongue 32, and finally another upwardly projecting tongue 33 positioned intermediate tongues 30 and 32. A trip lever 34 is pivoted intermediate of its ends between tongues 30, as at 35, and projects through aperture 31. Co-axial with pivot points 35 are springs 36, the ends of which act between the tongues 30 and the lever 34, each spring 80 urging the lever 34 in opposite directions, so that the lever normally remains vertical. A connecting link 37 is pivotally connected with lever 34, and the other end of the link is formed with an elongated slot, in which a pin 38 engages, said pin being supported in the upper end of a bell-crank 39, pivotally connected at 40 to tongue 33, and the other end of the bell-crank 39 has another pin 41, engaged in slot 42 of another connecting 85 link 43, the upper end of which engages one arm of bell-crank 44. The other arm of bell-crank 44 is connected to link 45, thereafter to several bell-cranks 46, and links 47, extending from the bottom of the locomotive 90 to the top. Another connecting link 48 is pivotally connected to lever 34, the other end of the link being formed with an elongated aperture 49, in which a pin 50 is engaged, said pin being secured in one arm of a bell-crank 51 pivotally mounted at 52 on tongue 33, and the other arm of the bell-crank 51 has another pin 53 engaged in elongated aperture 54 of the connecting link 43. Referring to Fig. 7 it will be noticed that the 100 elongated apertures are so constructed that when the bottom of lever 34 is moved to the right, link 48 moves bell-crank 51 which in turn moves link 43 downward, pulling one end of bell-crank 44 downward, while link 110

37 idles due to the elongated slot on the end of said link. Should the bottom of lever 34 be moved to the left, link 48 idles due to the elongated slot 49 in this link, and link 37 moves one arm of bell-crank 39, the other arm pulling downward on link 43, which in turn pulls downward on one arm of the bell-crank 44.

The uppermost link 47 connects with a link 55 having an aperture 56 and slidably guided by bracket 57 depending from the locomotive proper 15. Another bracket 58 is also fixed to the locomotive proper, and slidably supports a rod 59 normally urged forward by co-axially mounted spring 60. The rear of rod 59 is pivotally fastened to a lever 61 pivoted at 62 and having a connection lead 63. The top of link 55 is pivotally connected to another link 64 formed at one end with an elongated aperture 65 in which pin 66 engages. The pin 66 is supported in one arm of bell-crank 67 pivotally mounted as at 68, and the other arm of the bell-crank connects with link 69 having one end fastened to one arm of bell-crank 70 pivotally mounted at 71. The other arm of bell-crank 70 connects with the plunger 72 of the steam whistle 16.

In the operation of the device, as the signal 18 moves from the clear position to the danger position, the rod 20 communicates the motion to gear segment 22, thereafter to rack 23, rod 25 and finally to the cam element 26. In the danger position the cam element lies in the path of motion of trip lever 34, while in the clear position it is off the path of motion of the trip lever. Regardless of the direction of motion of the locomotive, as the trip lever is moved, the bell-crank 44 will be drawn downwardly, as previously explained. This motion is communicated to links 47, thereafter to link 55, and as the link 55 moves downwards, spring 60 causes rod 59 to engage in aperture 56, holding this link in its downward position until it is released by the locomotive operator's pulling connection 63. When the link is in the said downward position, the steam whistle operates, because of the connections therewith, namely bell-crank 70, link 69, bell-crank 67, link 64, and link 55. The locomotive operator may sound the whistle 16 by pulling line 69, and this motion will not affect other parts of the mechanism due to the pin 66 riding in slot 65.

In Figs. 3 and 4, a bracket 73 is shown depending from the locomotive bottom, and a plunger 74 to scrape the rails 17 is slidably mounted in the bracket, normally urged downward against the rails by a spring 75.

In Fig. 4 a modified form of cam element 26^a is shown, pivotally secured, as at 76 to a cross bar 77 supported between rails 17. The other end of cam element 26^a has a fastening means 78 for engagement with rod 25.

The rod 25 moves the cam element 26^a into and out of the line of movement of the trip lever 34.

Fig. 14 shows a modification of rod 25, namely the rod is formed of two parts 25^a and 25^b flexibly joined by means of a flange 82 on rod 25^a, said flange 82 engaging the ends of a bent member 80 slidably in a slot 81 in rod 25^a, the said rod 25^a having a cap member 79 slidable against the bent member 80, while spring 83 acts between cap member 79 and bent member 80. It is readily seen that rod 25^a may be pulled, and if for some reason rod 25^b cannot be moved, the spring 83 will give.

Fig. 15 shows the rod 25 connected to a bell-crank 95 pivoted at 96, and connecting rod 97 engages the bell-crank with another bell-crank 98 pivoted at 99. The bell-crank 98 has one arm connected with the switch points 100. If the switch is opened the cam element 26 is in line with the trip lever 34, while if closed the cam element is out of line with the trip lever 34.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new and desire to secure by United States Letters Patent is:

1. In a device of the class described, having a whistle on top of a locomotive proper, the combination of a bracket fastened to the bottom of said locomotive, said bracket having an aperture, a pair of tongues adjacent said aperture, a third tongue depending from said bracket, and a fourth tongue between said pair of tongues and said third tongue, a trip lever pivoted to said pair of tongues, means for resiliently holding said trip lever vertical, a link pivoted to said trip lever, said link being formed with an elongated aperture on one end, a bell-crank pivoted to said fourth tongue, a pin in one arm of said bell-crank engaging in said elongated slot, another pin in the other arm of said bell-crank, a second link having two elongated slots, said second pin engaging in one of said elongated slots, a bell-crank pivoted to said third tongue, said last mentioned link being connected with one arm of said bell-crank, a third link connected with said trip lever, said last mentioned link being formed with an elongated aperture, a pin engaged in said last mentioned aperture, a bell-crank pivotally connected to said fourth tongue, said last mentioned bell-crank supporting said last mentioned pin, and another pin in the last mentioned bell-

crank, said last mentioned pin engaging the second elongated aperture of said link with the two elongated apertures, and means connected with the bell-crank pivoted to said third tongue for operating said whistle.

2. In a device of the class described, having a whistle on top of a locomotive proper, the combination of a bracket fastened to the bottom of said locomotive, said bracket having an aperture, a pair of tongues adjacent said aperture, a third tongue depending from said bracket, and a fourth tongue between said pair of tongues and said third tongue, a trip lever pivoted to said pair of tongues, means for resiliently holding said trip lever vertical, a link pivoted to said trip lever, said link being formed with an elongated aperture on one end, a bell-crank pivoted to said fourth tongue, a pin in one arm of said bell-crank engaging in said elongated slot, another pin in the other arm of said bell-crank, a second link having two elongated slots, said second pin engaging in one of said elongated slots, a bell-crank pivoted to said third tongue, said last mentioned link being connected with one arm of said bell-crank, a third link connected with said trip lever, said last mentioned link being formed with an elongated aperture, a pin engaged in said last mentioned aperture, a bell-crank pivoted to said fourth tongue, said last mentioned bell-crank supporting said last mentioned pin, and another pin in the last mentioned bell-crank, said last mentioned pin engaging the second elongated aperture of said link with the two elongated apertures, and means connected with the bell-crank pivoted to said third tongue for operating said whistle, said latter means comprising a series of links and bell-cranks.

3. In a device of the class described, having a whistle on top of a locomotive proper, the combination of a bracket fastened to the bottom of said locomotive, said bracket having an aperture, a pair of tongues adjacent said aperture, a third tongue depending from said bracket, and a fourth tongue between said pair of tongues and said third tongue, a trip lever pivoted to said pair of tongues, means for resiliently holding said trip lever vertical, a link pivoted to said trip lever, said link being formed with an elongated aperture on one end, a bell-crank pivoted to said fourth tongue, a pin in one arm of said bell-crank engaging in said elongated slot, another pin in the other arm of said bell-crank, a second link having two elongated slots, said second pin engaging in one of said elongated slots, a bell-crank pivoted to said third tongue, said last mentioned link being connected with one arm of said bell-crank, a third link connected with said trip lever, said last mentioned link being formed with an elongated aperture, a pin engaged in said last mentioned aperture, a bell-crank pivoted to said fourth tongue, said last mentioned bell-crank supporting said last mentioned pin, and another pin in the last mentioned bell-crank, said last mentioned pin engaging the second elongated aperture of said link with the two elongated apertures, and means connected with the bell-crank pivoted to said third tongue for operating said whistle.

gaged in said last mentioned aperture, a bell-crank pivotally connected to said fourth tongue, said last mentioned bell-crank supporting said last mentioned pin, and another pin in the last mentioned bell-crank, 70 said last mentioned pin engaging the second elongated aperture of said link with the two elongated apertures, means connected with the bell-crank pivoted to said third tongue for operating said whistle, and means for 75 releasably locking said whistle in operating condition upon the operating of said trip lever.

4. In a device of the class described, having a whistle on top of a locomotive proper, 80 the combination of a bracket fastened to the bottom of said locomotive, said bracket having an aperture, a pair of tongues adjacent said aperture, a third tongue depending from said bracket, and a fourth tongue between 85 said pair of tongues and said third tongue, a trip lever pivoted to said pair of tongues, means for resiliently holding said trip lever vertical, said means comprising springs mounted co-axially with the pivot point of 90 said lever, the ends of said springs acting against said lever and said pair of tongues, and said springs acting in opposite directions, a link pivoted to said trip lever, said link being formed with an elongated aperture on one end, a bell-crank pivoted to said 95 fourth tongue, a pin in one arm of said bell-crank engaging in said elongated slot, another pin in the other arm of said bell-crank, a second link having two elongated 100 slots, said second pin engaging in one of said elongated slots, a bell-crank pivoted to said third tongue, said last mentioned link being connected with one arm of said bell-crank, a third link connected with said trip 105 lever, said last mentioned link being formed with an elongated aperture, a pin engaged in said last mentioned aperture, a bell-crank pivotally connected to said fourth tongue, said last mentioned bell-crank supporting 110 said last mentioned pin, and another pin in the last mentioned bell-crank, said last mentioned pin engaging the second elongated aperture of said link with the two elongated 115 apertures, and means connected with the bell-crank pivoted to said third tongue for operating said whistle.

5. In a device of the class described, having a whistle on top of a locomotive proper, 120 the combination of a bracket fastened to the bottom of said locomotive, said bracket having an aperture, a pair of tongues adjacent said aperture, a third tongue depending from said bracket, and a fourth tongue between 125 said pair of tongues and said third tongue, a trip lever pivoted to said pair of tongues, means for resiliently holding said trip lever vertical, a link pivoted to said trip lever, said link being formed with an elongated aperture on one end, a bell-crank 130

5 pivoted to said fourth tongue, a pin in one arm of said bell-crank engaging in said elongated slot, another pin in the other arm of said bell-crank, a second link having two elongated slots, said second pin engaging in one of said elongated slots, a bell-crank pivoted to said third tongue, said last mentioned link being connected with one arm of said bell-crank, a third link connected with said 10 trip lever, said last mentioned link being formed with an elongated aperture, a pin engaged in said last mentioned aperture, a bell-crank pivotally connected to said fourth tongue, said last mentioned bell-crank supporting said last mentioned pin, and another 15

pin in the last mentioned bell-crank, said last mentioned pin engaging the second elongated aperture of said link with the two elongated apertures, means connected with the bell-crank pivoted to said third tongue 20 for operating said whistle, and means for releasably locking said whistle in operating condition upon the functioning of said trip lever, said last mentioned means comprising a rod normally urged forward by a spring, and one link near said whistle being formed with an aperture engageable by said rod. 25

In testimony whereof I have affixed my signature.

OTTO ROESLER.
